UNITED STATES PATENT OFFICE.

ADOLPH H. C. HORNBOSTEL AND JAMES H. CROSWHITE, OF WAVERLY, MISSOURI.

COMPUTING DEVICE.

1,074,432.

Specification of Letters Patent. Patented Sept. 30, 1913.

Application filed December 14, 1912. Serial No. 736,868.

To all whom it may concern:

Be it known that we, ADOLPH H. C. HORNBOSTEL and JAMES H. CROSWHITE, citizens of the United States, residing at Waverly, in the county of Lafayette and State of Missouri, have invented certain new and useful Improvements in Computing Devices, of which the following is a specification, reference being had to the accompanying drawings.

This invention relates to computing devices and more particularly to that class in which the number of days from a date in one month to a certain date in another month may be quickly and easily determined.

An object of this invention is the provision of a computing device comprising a pair of disks, the disks being suitably lettered and numbered so that the number of days from a date in one month to a date in another month may be easily determined.

A further object of this invention is the provision of a computing device of this character comprising a spindle on which is rotatably mounted a disk having a peripheral flange, and a second disk rotatably mounted on the spindle within the flange of the first mentioned disk, a ring being secured to the flange to maintain the second disk in position, and means connected to the disks for preventing relative rotation thereof.

With these and other objects in view, this invention consists in certain novel constructions, arrangements, and combinations of parts to be hereinafter more fully described, claimed and illustrated in the accompanying drawings, in which—

Figure 1 is a front elevation of the device; Fig. 2 is a side elevation thereof; Fig. 3 is a vertical section; Fig. 4 is an enlarged detail section, and Fig. 5 is a section taken on the line 5—5 of Fig. 3.

Referring more particularly to the drawing, the numeral 1 designates a base plate which is formed with a standard 2, the standard being formed with a laterally extending spindle or shaft 3. Rotatably mounted on the shaft near the inner end

thereof, is an annular plate or disk 4 which is provided with a laterally extending flange 5, the disk 4 being prevented from lateral movement on the shaft by means of plates 6 keyed to the shaft on the opposite sides of the disk. Mounted on the shaft 3 near the outer end thereof is a disk 7, movement of the disk inwardly on the shaft being limited by a plate 8 which is keyed thereon. The disk 7 is formed with an offset peripheral flange 9, which is adapted to bear against a ring 10, which is secured to the outer edge of the flange 5 by bolts 11 or other suitable fastening devices. The inner peripheral edge of the ring 10 is adapted to engage the shoulder 12 formed on the disk 7 by the offset flange 9 so that the outer faces of the disk 7 and the ring are flush.

A milled knob 13 is secured to the outer face of the disk 7 and is formed with an opening 14 to receive the outer end of the spindle 3, the knob forming suitable means whereby the disk 7 may be rotated. Secured to the inner face of the flange 5 is an apertured supporting member 15 in which is slidably mounted one end of a bolt or stem 16, the opposite end of the bolt extending through the ring 10. An expansion spring 17 is coiled around the bolt, one end thereof bearing against the supporting plate 15 and the opposite end of the spring bearing against a plate 18 which is secured to the bolt 16 and which is formed on its outer face with a tooth 19 which is adapted to engage with an annular series of teeth 20 formed on the inner face of the offset flange 9 of the disk 7. It will be seen that when the bolt 16 is in normal position with the plate 18 engaged with the tooth flange 9 of the disk 7, the disks 4 and 7 can only be rotated simultaneously, but when the bolt is moved inwardly so that the plate 18 is disconnected from the flange, the disks may be rotated independently of each other.

The front face 21 of the ring 10 is subdivided into 365 spaces, the spaces being inscribed with numbers in regular progression from 1 to 365 to represent the days of the year. The outer face of the disk 7,

which constitutes the dial of the device, has marked upon it a number of concentric annular spaces, the outer annular space 22 being also divided into 365 sub-divisions, 5 and the next annular space 23 being divided into 12 sub-divisions which are lettered in regular progression with the names of the twelve months of a year. The inner annular space 24 may be utilized for 10 advertising purposes, if desired. The sub-divisions in the outer annular space 22 of the disk 7 are numbered to correspond with the number of days in the month indicated in the sub-divisions in the annular space 23. 15 To determine the number of days from one date in one month to a certain date in another month, in the space 23, the date in the annular space 22 from which it is desired to count, is set opposite the numeral 1 20 on the ring 10, and the number in the space on the ring opposite the day of the month to which it is desired to count will indicate the number of days between the given dates.

On the outer periphery of the flange 5 is 25 inscribed an interest table 25 for computing interest on one dollar, at different percentages from 1 to 365 days. The interest for one day is marked in the spaces adjacent the numeral 1 on the outer face of the ring, 30 so that when the number of days from one date to a given date has been found and it is desired to determine the interest on one dollar for that number of days, it is only necessary to look in the space showing the 35 required per cent. adjacent the space on the ring showing the number of days.

From the foregoing it is obvious that the number of days from a date in one month to a certain date in another month may be 40 quickly and easily determined, and that the device is composed of a small number of parts whereby it may be cheaply manufactured. It will be seen that the ring 10 limits the outward movement of the disk 7 45 on the spindle 3, and the plate 8 limits the inward movement of the disk, whereby the lateral movement of the disk in either direction is prevented.

Having thus fully described our invention 50 what we desired to claim and secure by Letters Patent is:

1. A device of the character described comprising a spindle, a disk having an annular flange rotatably mounted on said spindle, a second disk rotatably mounted on said spindle within said flange, said second disk being formed with a series of teeth, and means 55 slidably connected to the first mentioned disk and adapted for engagement with said teeth, whereby independent rotation of the disks is prevented, as and for the purpose described.

2. A device of the character described comprising a spindle, a disk having an annular flange rotatably mounted on said spin-

dle, a second disk rotatably mounted on said spindle within said flange, said second disk being formed with a series of teeth, a ring secured to the outer edge of said flange, a bolt slidably disposed in said ring, and means connected to said bolt and adapted for engagement with the teeth of said second disk, whereby independent rotation of the disks is prevented, as and for the purpose described. 70

3. A device of the character described comprising a spindle, a disk having a laterally extending peripheral flange rotatably mounted on said spindle, a second disk rotatably mounted on said spindle within said flange, a ring secured to the outer edge of said flange, means whereby lateral movement of said disks is prevented, and means formed on said second disk for locking engagement with said ring, as and for the 80 purpose described.

4. A device of the character described comprising a spindle, a disk having a laterally extending flange rotatably mounted on said spindle, a second disk rotatably mounted on said spindle within said flange, a ring secured to the outer edge of said flange, an inwardly offset peripheral flange formed on the second disk and adapted to bear against the inner face of said ring, and means secured to the flange on the first mentioned disk and adapted for engagement with the flange on the second mentioned disk whereby rotary movement of the disks independent of each other is prevented. 90

5. A device of the character described comprising a spindle, a disk rotatably mounted on said spindle, said disk having a transversely extending peripheral flange, a second disk rotatably mounted on said spindle within said flange, a ring secured to the outer edge of said flange, a plate secured to the inner face of said flange near the outer end thereof, and means supported by said plate for engagement with said second disk, whereby rotary movement of said disks independent of each other is prevented. 95

6. A device of the character described comprising a spindle, a disk rotatably mounted on said spindle, said disk having a transversely extending peripheral flange, a second disk rotatably mounted on said spindle within said flange, said second disk having an annular series of teeth, and means secured to the first mentioned disk and adapted to engage said teeth in the second mentioned disk whereby rotary movement of said disks independent of each other is prevented. 105

7. A device of the character described comprising a spindle, a disk rotatably mounted on said spindle, said disk having a transversely extending peripheral flange, a second disk rotatably mounted on said spindle within said flange, said second disk 115

having an annular series of teeth, a plate secured to the inner face of said flange, and means slidably supported in said plate for engagement with said series of teeth where-
5 by rotary movement of said disks independ-
ent of each other is prevented.

In testimony whereof we hereunto affix

our signatures in the presence of two wit-
nesses.
